R. Grant,
Charging Soda Fountains.
N° 73,712. Patented Jan. 28, 1868.

Oldsmith

Inventor:

Robert Grant.

United States Patent Office.

ROBERT GRANT, OF BROOKLYN, NEW YORK.

Letters Patent No. 73,712, dated January 28, 1868; antedated January 17, 1868.

IMPROVED APPARATUS FOR CHARGING WATER WITH CARBONIC ACID.

The Schedule referred to in these Letters Patent and making part of the same.

TO ALL WHOM IT MAY CONCERN:

Be it known that I, ROBERT GRANT, of the city of Brooklyn, in the county of Kings, and State of New York, have invented certain new and useful Improvements in Apparatus for Making Portable Compressed or Condensed Carbonic Acid Gas, or other gases for manufacturing soda-water, or for other purposes of impregnating fluids with carbonic acid gas or other gases; and I hereby declare the following to be a full, clear, and exact description thereof, reference being had to the accompanying drawings, which are lettered to correspond with and form a part of the specification.

In order that the public may fully understand the nature of my invention, and those skilled in the mechanic arts be enabled to construct and use the same, I will describe it as follows, to wit:

Figure 1 is a perspective drawing of my apparatus. Letter A is the compressed-gas cylinder; B is the water-tank; C is the gas-regulator; D is the ice-box, or refrigerating-chamber; E is a mercury-gauge; F is the eduction-pipe from the water-tank to the gas-injector, P, fig. 2; N is the gas-injecting chamber; O is the induction-water pump; R is the equalizing-pipe from the regulator to the water-tank; S is the draught-cock; T is the pipe connecting the compressing-cylinder A with the regulator C; M is the induction-water pipe; W is the water-gauge; X is the cock that controls the flow of the gas from the regulator to the injector P; Z is the stop-cock controlling the flow of gas from the regulator to the water-tank.

Figure 2 is a vertical section of the gas-injecting chamber N, showing the injector-gas jet P and the water-regurgitating valve V.

Figure 3 is a perspective sectional drawing of the gas-regulator C. 2 is the gas-regurgitating valve; 3 is the gas-regulating-screw valve; 8 is the gas-induction orifice; 9 is the stem of the air-tight plunger, which is operated by means of a spiral spring and the pressure of the gas, and which operates the screw-valve 3 by means of the toggle-joint 6.

Figure 4. Letter D is the ice-box or refrigerating-chamber containing the mixing-coil and cooler.

Figure 5 is a vertical section of the water-tank B, showing the horizontal shaft 1, and crank 2, stuffing-boxes 3 3', and the revolving mixing-fans 4 4' 4" secured to a gland, 5, the same being secured to the shaft 1 by means of a set-screw 6'. The top of the tank B is secured, by lugs and screws for fastening the same, to the body of the tank with a suitable packing. This tank may be lined with tin or any other non-oxidizing material. 7 is an exhaust-cock for exhausting the air from the water-chamber when the apparatus is put in action.

Mode of Operating the Apparatus.

First fill the portable cylinder A with compressed or condensed gas, under an atmospheric pressure of from four hundred and fifty to six hundred pounds to the square inch; then attach the cylinder to the regulator C, by means of the coupling T, (see fig. 1;) then turn on the full pressure of gas from the cylinder A to the regulator C, through the induction-pipe, by means of the stop-cock G, fig. 1, the regulator being graduated ninety pounds pressure to the square inch, through the eduction-pipe, by means of the air-tight plunger and spiral spring operating upon the screw-valve 3, by the toggle-joint 6, fig. 3, which is actuated by the pressure of the gas in the regulator; then fill the water-tank B, fig. 1, with water, by means of the pump O, letting off the air through the exhaust-cock 7, fig. 3; then turn on the pressure of the gas from the regulator to the water-tank, by means of the stop-cock, at the same time revolving the fans 4 4' 4", by means of the crank 2', fig. 5, for the purpose of effecting a partial absorption of the superinduced gas, by the water in the tank B. This rotation I continue at intervals. As the fresh water is pumped into the tank again, I turn the pressure of the gas from the regulator to the injector G, fig. 2, by means of the stop-cock X, figs. 1 and 2.

When I wish to draw soda-water, I open the draught-cock S, fig. 4. That allows the water to flow through the mixing-coil, under a pressure of ninety pounds to the square inch, from the water-tank B. As this water passes the injector P, fig. 2, the gas mingles intimately with the water through the jet P, under a pressure. As the water and gas pass through the mixing-coil, the combination becomes complete by the final absorption of the gas by the water.

I do not confine myself to the above arrangement alone, from the fact that it may be found necessary to use the individual parts, or modifications thereof, separately, and otherwise adapted for similar purposes, to suit the time and exigencies of the situation.

I am aware that water has been pumped, against the pressure of gas, in soda-fountains, which gas remains in the fountain after the soda-water has been drawn off, preparatory to refilling the fountain with water for the purpose of again manufacturing gas, and compressing the same to form the full equivalent of soda-water. This was done for the purpose of saving the residuum of gas in the fountain after the soda-water was drawn off. But by my improved process I effect a continuous manufacture of soda-water, under the equivalent automatic pressure of gas, never allowing the fountain to become exhausted, nor requiring a separate process of manufacturing and refilling the fountain with gas and water after the soda-water was exhausted.

In effecting the process of filling the water-tank B with water, I do not confine myself to the pump o, fig. 1, as the same result can be produced by means of a reservoir of water, placed at a sufficient elevation, and connecting with the water-induction pipe m, fig. 1. Also in this case, not only the pump, but likewise the water-tank B itself, may be dispensed with; if desirable, by simply connecting the induction-water pipe m immediately to the water-pipe F, fig. 1, the compressing of the gas with the water taking place sufficiently well at the juncture of the gas-injector P, and in the mixing-coil the flow of the gas being controlled by the stop-cock X.

The nature of my invention consists in the use of detachable cylinders, of compressed or condensed gas or gases; operating a mixer or injector, wherein gases are combined with water, in any locality, thus avoiding the necessity of transporting the water for the purpose of making mineral or effervescent fluids for drinking or other purposes; also for the purpose of avoiding the commingling of the gas or gases and water in the compressing-cylinder A, thereby obviating the oxidization of the interior of the cylinder A, and rendering it unnecessary to line said cylinder with any unoxidizing substance, as the dry gas does not affect the metal thereof, thus rendering the transportable cylinders compact, light, strong, and cheaply constructed for use.

Therefore, what I claim as novel and useful, and what I wish to secure by Letters Patent of the United States, is—

1. The cylinder A, regulator C, injector P, water-tank B, and regurgitating-valves 2 and 3, arranged and operated as described, and shown in the drawings, or otherwise modified for the purpose set forth.
2. I claim the continuous automatic process of compressing carbonic acid or other gases in water by the means substantially as described, and for the purposes above set forth.

In testimony whereof, I have hereunto subscribed my name in the presence of two witnesses.

ROBERT GRANT.
